LAMP SOCKET MOUNTING FIXTURE

Carl X. Meyer, St. Louis County, and Leo G. Stahlhut, Kirkwood, Mo., assignors to Day-Brite Lighting, Incorporated, St. Louis, Mo., a corporation of Missouri

Application February 4, 1955, Serial No. 34,358

Term of patent 14 years

(Cl. D48—23)

FIG.1.

FIG.2.

FIG.3.

FIG.5.

FIG.4.

FIG.6.

Fig. 1 is an elevational view of the outer end of a lamp socket mounting fixture, showing our new design, Fig. 2 is a side elevational view thereof,

Fig. 3 is a top plan view of the same socket mounting fixture,

Fig. 4 is an elevational view of the side opposite Fig. 1,

Fig. 5 is a perspective view as seen from below, and

Fig. 6 is a perspective view of the outer end of the mounting fixture seen from below.

The broken lines shown in the drawing are for illustrative purposes only.

We claim:

The ornamental design for a lamp socket mounting fixture, as shown and described.
